Primary Examiner — John R Yeh(74) *Attorney, Agent, or Firm* — Jose Cherson Weissbrot(57) **CLAIM**

The ornamental design for a mop as shown and described.

DESCRIPTION

FIG. 1 is a front perspective view of a mop showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a partial enlarged view of FIG. 1;

FIG. 10 is a partial enlarged view of FIG. 1;

FIG. 11 is a partial enlarged view of FIG. 2;

FIG. 12 is a partial enlarged view of FIG. 3;

FIG. 13 is a partial enlarged view of FIG. 3;

FIG. 14 is a partial enlarged view of FIG. 4; and,

FIG. 15 is a partial enlarged view of FIG. 4.

The dash-dash broken lines in the figures depict portions of the mop that form no part of the claimed design, the dash-dot-dash broken lines are for annotating enlarged views that form no part of the claimed design.
